[57] — CLAIM

The ornamental design for a housing for an electrical connector, as shown and described.

DESCRIPTION

FIG. 1 is a top, front perspective view of a housing for an electrical connector showing our new design;

FIG. 2 is a front elevation view thereof;

FIG. 3 is a top plan view thereof;

FIG. 4 is a right side elevation view thereof, the left side being a mirror image;

FIG. 5 is a bottom plan view thereof;

FIG. 6 is a rear elevation view thereof;

FIG. 7 is a cross-section thereof as taken along line 7—7 of FIG. 2;

FIG. 8 is a cross-section thereof as taken along line 8—8 of FIG. 2;

FIG. 9 is a cross-section thereof as taken along line 9—9 of FIG. 2;

FIG. 10 is a cross-section thereof as taken along line 10—10 of FIG. 4;

FIG. 11 is a top, front perspective view of a second embodiment of our new design;

FIG. 12 is a front elevation view thereof;

FIG. 13 is a top plan view thereof;

FIG. 14 is a right side elevation view thereof, the left side being a mirror image;

FIG. 15 is a bottom plan view thereof;

FIG. 16 is a rear elevation view thereof;

FIG. 17 is a cross-section thereof as taken along line 17—17 of FIG. 12;

FIG. 18 is a cross-section thereof as taken along line 18—18 of FIG. 12;

FIG. 19 is a cross-section thereof as taken along line 19—19 of FIG. 12;

FIG. 20 is a cross-section thereof as taken along line 20—20 of FIG. 14;

FIG. 21 is a top, front perspective view of a third embodiment of our new design;

FIG. 22 is a front elevation view thereof;

FIG. 23 is a top plan view thereof;

FIG. 24 is a right side elevation view thereof, the left side being a mirror image;

FIG. 25 is a bottom plan view thereof;

FIG. 26 is a rear elevation view thereof;

FIG. 27 is a cross-section thereof as taken along line 27—27 of FIG. 26;

FIG. 28 is a cross-section thereof as taken along 28—28 of FIG. 26; and

FIG. 29 is a cross-section thereof as taken along line 29—29 of FIG. 24.
